Inventor:

UNITED STATES PATENT OFFICE.

MARY MATILDA CHEESEMAN, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,139, dated July 15, 1884.

Application filed May 23, 1884. Term of patent 3½ years.

To all whom it may concern:

Be it known that I, MARY MATILDA CHEESEMAN, of the city, county, and State of New York, have invented and produced a new 5 and original Design for a Pattern of a Lady's Costume, (numbered 9,259;) and I do hereby declare that the engraved prints accompanying this specification convey to any one accustomed to using paper patterns a clear understanding of how a garment made up by the pattern will appear.

The design shows a round walking-skirt and an overdress. The skirt exhibits a cluster of seven tucks in its lower part. The over- 15 dress displays close-fitting basque-fronts, with deep box-plaited draperies depending from them, flaring slightly below the basque-clos-

ing, and extending nearly to the lower edge of the skirt; a close-fitting back extending the same depth upon the skirt, and displaying under-folded plaits at the lower ends of its body-seams; a deep round collar that displays a fastening at the center of the front; a standing collar, and coat-sleeves showing gathers and a high roll at the shoulders. 20

What I claim as my invention, and desire to secure by Letters Patent, is—

The design for a lady's costume, as shown in the engraved prints accompanying this specification.

MARY MATILDA CHEESEMAN.
